CARBOXIMIDE COMPOUNDS

Hsing Yun Fan and Harry G. Durham, Modesto, Calif., assignors to Shell Oil Company, a corporation of Delaware

No Drawing. Filed Dec. 30, 1957, Ser. No. 705,787

11 Claims. (Cl. 260—326)

The present invention is concerned with hydrocarbons wherein one terminal position is occupied by a polyhalogenopolycycloalkene and the other terminal position is occupied by a dicarboximide or derivatives thereof. These compounds have been found to possess significant toxicity toward and inhibition of a wide variety of fungi.

The need for efficient and economical fungicidal and fungistatic compositions has long been manifest. In spite of this fact, however, a vast number of the compounds employed as fungicides have generally been found lacking in one or more of the basic requirements of a satisfactory fungicide. In order to be commercially useful, a fungicidal composition must be compatible with adjuvants and other active ingredients; it must be economical; it should be soluble in common solvents and stable; and most important, it must not be toxic to the plants to which it is applied or to animal life. A prohibitive degree of phytotoxicity under the conditions utilized for fungus control and toxicity toward warm blooded animals are among the most common shortcomings of present fungicides.

It is, consequently, the principal object of the present invention to provide new and novel compounds which are effective as fungicides yet do not manifest prohibitive toxicity toward warm blooded animals such as man.

Another object of the present invention is to provide new and novel fungicidal compounds which can be economically prepared, distributed and applied to plants.

Yet another object of the present invention is to provide economical and stable fungicidal compositions containing these compounds.

Still another object of the present invention is to provide a method of combating fungi by applying these compositions to plants.

Other objects and advantages will be apparent from the following description read in conjunction with the appended claims.

Generally speaking, the present invention is concerned with organic compounds wherein one terminal position is occupied by a polyhalogenopolycycloalkene and the other terminal position is occupied by dicarboximide or derivative thereof. The term dicarboximide as employed throughout this specification refers to the group

Of the polyhalogenopolycycloalkenes which occupy one terminal position of the compounds encompassed by the present invention, halogenated bicyclo(2.2.1)hept-5-ene rings as shown in the following structural formula are preferred:

2

Of equal interest in the dimethanonaphthalene ring structure shown in the following structural formula:

5

10 The present invention also encompasses the polycyclic structure shown in the following structural formula:

15

20 This basic carbon skeleton consists of not more than five linearly fused five membered rings.

The halogenated cycloalkene portion of the molecule may be attached directly to the nitrogen atom of the dicarboximide portion of the molecule, or alternatively, 25 the terminal portions of the molecule may be separated by an alkyl radical of from 1 to 10 carbon atoms, or an aryl radical such as benzyl, tolyl, phenyl, naphthalenyl, or anthracenyl group or an aralkyl group, the alkyl portion of which has 1 to 10 carbon atoms and the aryl portion of which is a benzyl, tolyl, phenyl, naphthalenyl or anthracenyl group.

In these formulae X represents hydrogen or halogen (preferably chlorine) and X' represents hydrogen, halogen (preferably chlorine) or an alkoxy (preferably methoxy) group. At least one X should be a halogen.

R may be a straight chain, branched chain or cyclic alkylene group of from 1 to 10 carbon atoms, an arylene group such as a tolylene, phenylene, naphthylene or anthrylene or an aralkylene group made up of the alkylene 40 as described above and arylene groups. R is preferably a short chain alkylene group. y is 0 to 10.

W represents a straight chain aliphatic group of 2 to 5 carbons (preferably 2) either saturated or having one or 45 more double bonds. W may be partially or totally halogenated, preferably with chlorine. W may also represent an aryl radical such as benzene, toluene, naphthalene and anthracene or their halogenated derivatives. Each of 2 carbon atoms of W are bonded respectively to each of the two carboxyl groups of the decarboximide. When 50 W is an aryl ring, each of two adjacent carbon atoms of the aryl rings are bonded to a carboxyl group of the dicarboximide. The compounds of the present invention may thus be considered as dicarboximides having substituted therein halogenated polycyclic structures such as a polyhalopolycycloalkenyl radical or a halogenated 1,4,5,8-dimethanonaphthyl radical.

Illustrative of the types of compounds envisioned by the present invention are:

60 N - (1,4,5,6,7,7-hexachlorobicyclo(2.2.1)hept-5-en-2-yl)-maleimide.

N - (1,4,5,6,7,7-hexachlorobicyclo(2.2.1)hept-5-en-2-ylmethyl)maleimide.

2 - chloro-N-(1,4,5,5,7,7-hexachlorobicyclo(2.2.1)hept-5-en-2-ylmethyl)maleimide

- N - (5,6,7,8,9,9 - hexachloro-1,2,3,4,4a,5,8,8a-octahydro-1,4,5,8-dimethano-naphthalen-2-ylmethyl)maleimide
 2,3 - dichloro - N-(1,4,5,6,7,7-hexachlorobicyclo(2.2.1)-hept-5-en-2-ylmethyl)succinimide
 N - (1,4,5,6,7,7-hexachlorobicyclo(2.2.1)hept-5-en-2-ylmethyl)phthalimide
 N - (1,4,5,6,7,7-hexabromobicyclo(2.2.1)hept-5-en-2-yl)-maleimide
 2,3 - difluoro - N-10-(1,4,5,6,7,7-hexafluorobicyclo(2.2.1)-hept-5-en-2-yldecyl)pimelimide
 2,3 - dibromo - N-(1,4,5,6-tetrabromo-7,7-dimethoxybicyclo(2.2.1)hept-5-en-2-ylmethyl)succinimide
 N - 2 - ((1,4,5,6-tetrabromo-7,7-diphenoxybicyclo(2.2.1)-hept-5-en-2-yl)ethyl)succinimide
 N - (1,4,5,6,7,7 - hexachlorobicyclo(2.2.1)hept-5-en-2-yl-tolyl)maleimide
 2 - fluoro - N - (1,4,5,6,7,7-hexabromobicyclo(2.2.1)hept-5-en-2-ylbenzyl)maleimide
 N - (5,6,7,8,9,9 - hexabromo-1,2,3,4a,5,8,8a-octahydro-1,4,5,8-dimethanonaphthalen-2-ylphenyl)maleimide
 N - (1,4,5,6,7,7 - hexachlorobicyclo(2.2.1)hept-5-en-2-yl-anthryl)maleimide
 N - (1,4,5,6,7,7 - hexachlorobicyclo(2.2.1)hept-5-en-2-yl-naphthyl)maleimide

Generally speaking, the maleimides of the present invention may be prepared by reacting the corresponding maleamic acid with acetic anhydride and the phthalimides of the present invention may be prepared by reacting the corresponding amine with phthalic anhydride. The maleamic acids themselves are obtained by reacting the appropriate polyhalogenopolycycloalkene amine with maleic anhydride. Detailed preparation of these maleamic acids is to be found in co-pending application Serial Number 705,782. The preparation of the amines is described in copending application Serial Number 705,781.

Examples of specific preparations of compounds encompassed by the present invention follow:

EXAMPLE I

N-(5,6,7,8,9,9-hexachloro-1,2,3,4,4a,5,8,8a-octahydro-1,4,5,8-dimethanonaphthalen-2-ylmethyl)maleimide

A mixture of 54 g. of N-(5,6,7,8,8-hexachloro-1,2,3,4,4a,5,8,8a - octahydro-1,4,5,8-dimethanonaphthalen-2-ylmethyl)maleamic acid, 90 ml. of acetic anhydride and 3 g. of sodium acetate was heated at 70° for 16 hours then 2 hours at 90°. The solution was poured into 250 ml. of water and stirred until solid formed. The crude solid was recrystallized from benzene to give 15 g. of semi-pure product, M.P. 156-62°. The benzene filtrate was taken to dryness and extracted with hexane. The hexane extract was taken to dryness and the residue triturated with benzene. The benzene extract was taken to dryness and the residue triturated with methanol to give more solid, 13 g. M.P. 150-8°. Recrystallization of the two combined crops gave 21 g. M.P. 160-2°, of pure product of 40% yield. Analysis: Calcd. for $C_{17}H_{13}Cl_6NO_2$: Cl, 44.6. Found: Cl, 44.3.

EXAMPLE II

N-(1,4,5,6,7,7-hexachlorobicyclo(2.2.1)hept-5-en-2-ylmethyl)phthalimide

A solution of 37 g. of 1,4,5,6,7,7-hexachlorobicyclo(2.2.1)hept-5-ene-2-methylamine hydrochloride in 200 ml. of water was made alkaline to phenolphthalein with 20% NaOH solution and extracted with hexane. The hexane solution of free amine was then added to a solution of 15 g. of phthalic anhydride in 200 ml. of benzene. After 20 minutes reflux a solid fell out. It was collected to give 45 g. of N-(1,4,5,6,7,7-hexachlorobicyclo(2.2.1)hept-5-en-2-ylmethyl)phthalimide, M.P. 180-180.5°, in 92% yield. Analyses: Calcd. for $C_{16}H_{11}Cl_6NO_2$: Cl, 44.6; neut. equiv. 478. Found: Cl, 44.5; neut. equiv. 480.

The phthalimide was heated for 20 minutes at 180.5°. It evolved water and gave a colorless liquid

which solidified on cooling. The residue was recrystallized from hexane to give 25 g. (60%) of the pure phthalimide, M.P. 131-2°, after one further recrystallization from methanol. Analysis: Calcd. for $C_{16}H_9Cl_6NO_2$: Cl, 46.3. Found: Cl, 46.0.

EXAMPLE III

N-(1,4,5,6,7,7-hexachlorobicyclo(2.2.1)hept-5-en-2-yl)maleimide

- 10 A total of 30 g. of N-(1,4,5,6,7,7-hexachlorobicyclo(2.2.1)hept-5-en-2-yl)maleamic acid was added to a well stirred solution of 40 ml. of acetic anhydride and 1.5 g. of sodium acetate at 90-5°. The mixture was kept at 90-5° for 1.5 hours after the end of the addition then it was poured into water. The solid which formed was collected and extracted with hot hexane leaving 25 g. of crude product, M.P. 161-4°. Recrystallization of this material from hexane gave 11 g. of pure product, M.P. 166.9°. Analysis: Calcd. for $C_{11}H_6Cl_6NO_2$: Cl, 53.8. Found: Cl, 53.5. Repetition of the above experiment and further workup with the mother liquor from the above experiment gave 21 g. of solid, M.P. 164-6° and 10 g. of solid, M.P. 163-5°. The total of 42 g. of N-(1,4,5,6,7,7 - hexachlorobicyclo(2.2.1)hept - 5 - en-2-yl)maleimide is a 75% overall yield.

EXAMPLE IV

2-chloro-N-(1,4,5,6,7,7-hexachlorobicyclo(2.2.1)hept-5-en-2-ylmethyl)maleimide

- 30 To a well stirred solution of 50 ml. of acetic anhydride and 3 g. of sodium acetate at 100° was slowly added 58 g. of 2 - chloro-N-(1,4,5,6,7,7-hexachlorobicyclo(2.2.1)hept-5-en-2-ylmethyl)maleamic acid. The resulting solution was kept at 100° for 30 minutes then poured into 400 ml. of water and allowed to stand for 24 hours. The water insoluble gum formed was dissolved in hot hexane but failed to crystallize upon cooling the solution. The hexane was removed and a portion of the oil crystallized from cold pentane to give 1 g. of product, M.P. 76-8°. The mother liquor was concentrated and distilled to give a colorless liquid, B.P. 190-210° (0.5-1.0 mm.). Recrystallization of the distillate from pentane gave 40 g. (75%) of the desired product, M.P. 75-6°. Analysis of material, M.P. 76-8°. Calcd. for $C_{12}H_6Cl_7NO_2$: Cl, 55.9. Found: Cl, 55.8.

EXAMPLE V

N-(1,4,5,6,7,7-hexachlorobicyclo(2.2.1)hept-5-en-2-ylmethyl)maleimide

- 50 There was added 46 grams of N-(1,4,5,6,7,7-hexachlorobicyclo(2.2.1)hept-5-en-2-ylmethyl)maleamic acid to 60 grams of acetic anhydride and 2 grams of anhydrous sodium acetate stirred at 80°. The mixture was kept at 100° for one hour then poured into 300 ml. of water and allowed to stand overnight. A total of 48 grams of crude N-(1,4,5,6,7,7-hexachlorobicyclo(2.2.1)hept-5-en-2-ylmethyl)maleimide was collected. The crude was dissolved in hot hexane and the solution was filtered. Cooling the filtrate gave 13 grams of solid, M.P. 107-109° which had M.P. of 108-110° after one more recrystallization from hexane. This in turn was raised to 112-113.5° upon further recrystallization from methanol. Workup of the mother liquors gave 26 grams of solid, M.P. 112-113° from methanol. The yield was 60%. Further recrystallization of the 112-113.5° material from methanol gave analytical material, M.P. 113-114°. Calcd. for $C_{12}H_7Cl_6NO_2$: C, 35.2; H, 1.7; Cl, 52.0. Found: C, 35.2; H, 1.5; Cl, 52.1.

EXAMPLE VI

2,3-dichloro-N-(1,4,5,6,7,7-hexachlorobicyclo(2.2.1)hept-5-en-2-ylmethyl)succinimide

- 75 Chlorine was passed into a solution of 45 grams of N - (1,4,5,6,7,7 - hexachlorobicyclo(2.2.1)hept - 5 - en-yl-

(methyl)maleimide (Example V) in 200 ml. of CHCl_3 at 30° for 30 minutes. Workup gave only unchanged starting material. This was redissolved in 110 ml. CHCl_3 and chlorinated under U.V. irradiation for 2.5 hours. The solvent was removed and the residue triturated with hexane to give a solid M.P. 118-122°. One recrystallization from heptane gave 45 grams of product (86%), M.P. 122-126°. Recrystallization from benzene gave 34.5 grams of solid M.P. 125-132° C., 6.5 grams of solid, M.P. 122-129°. Analyses of solid melting at 125-132°. Calcd. for $\text{C}_{12}\text{H}_7\text{Cl}_8\text{NO}_2$: C, 29.9; H, 1.45; Cl, 59.0. Found: C, 30.4; H, 1.7; Cl, 59.0.

The compounds of the present invention possess fungicidal activity to a wide variety of plant pathogens. In the foliage fungicide screen, three varieties of bean plants and four foliage fungus diseases were employed. Employing these hosts and pathogens the chemicals were

10

To facilitate deposit, the primary leaves are oriented to a vertical position by pinning them to a small wire staff. Either the upper or lower epidermis of the leaf is exposed to the spray stream, depending on the surface to be inoculated.

5 When the mist type spray and the diluent mixture is applied, a drying interval of 1-2 hours is sufficient before inoculation with spore suspensions using a specially constructed atomizer. Inoculations with bean mildew are made by dusting conidia over treated plants in the greenhouse.

10 After 24 hours' incubation at 19° C. and 100% humidity, the plants are removed to the controlled environment greenhouse for symptom development. Disease control and phytotoxicity assessments are made within 7 days.

15 The following table summarizes the results of screening:

TABLE 1.—FOLIAGE FUNGICIDE SCREEN

	Disease Control Min. Effective Conc. (p.p.m.)				Phytotoxicity Max. "Safe" Conc. (p.p.m.)		
	P.p. ^a	E.p.	U.p.	C.I.	L. ^b	P.	BV

^a P.p. = *Phytophthora phaseoli* (downy mildew of lima bean); E.p. = *Erysiphe polygoni* (bean powdery mildew); U.p. = *Uromyces phaseoli* (bean rust); C.I. = *Colletotrichum*.

^b L = Lima bean, P = Pinto bean, BV = Black Valentine bean.

screened for general as well as specific control activity and for phytotoxicity. Diseases and hosts are shown below:

BEAN HOSTS
Phaseolus vulgaris var. Pinto
P. vulgaris var. Black Valentine
P. limensis var. Fordhook
 242

PATHOGENS
Uromyces phaseoli var. *typica* (rust)
Erysiphe polygoni (powdery mildew)
Collectotrichum lindemuthianum (anthracnose)
Phytophthora phaseoli (downy mildew)

These four bean pathogens are of economic importance and represent each of the four classes of fungi. *P. phaseoli* is closely allied with *P. infestans*, the important potato and tomato pathogen. Thus, with the above selection, chemicals can be routinely screened for general or specific disease control activity and for phytotoxicity on a moderately susceptible plant type.

The test is carried out according to the following procedure: Test chemicals are prepared as 1% w./v. stock solutions in a solvent. The stock is diluted for spraying using a diluent consisting of distilled water + solvent (1:1 or with distilled water plus two solvents (2:1:1). Triton X-155, at 0.005% w. is used as a wetting agent for each concentration of toxicant. All chemicals are initially tested at a single concentration of 1000 p.p.m. If acceptable disease control is shown, the chemicals are retested at 1000 p.p.m. and the next lowest dilution of 500 p.p.m. Chemicals continuing to show disease control are retested in this fashion until the minimum effective concentration is determined. Phytotoxicity assessments are expressed as the maximum "Safe" concentration.

Spray applications are made using a laboratory sprayer. The bean plants are selected for use at a stage when the two primary leaves are about three-quarters expanded.

45 The effectiveness of the present compounds as fungicides is further evidenced by the following tests:

To obtain expanded disease control data, chemicals were sprayed as emulsions, solutions, or suspensions using concentrations of 0.24% w., 0.12% w. and 0.06% w. These correspond respectively to 2, 1, and 0.5 pound of toxicant per 100 gallons of spray. Plants were sprayed to their run-off stage, dried for 24 hours, and inoculated with test fungus spores. After inoculation, the plants were held for 24-48 hours in a humidified incubation chamber at 19° C. They were then removed to the greenhouse for disease and phytotoxicity development.

55 Crops and diseases used were tomato or potato blight (*Phytophthora infestans*), celery blight (*Septoria apii-graveolentis*), bean mildew (*Erysiphe polygoni*), bean rust (*Uromyces appendiculatus*), and cucumber anthracnose (*Colletotrichum lagenarium*).

60 From four replicated plants per concentration, a percentage disease control figure was obtained, which was based upon the improvement shown over the untreated checks as follow:

$$65 \frac{(\text{disease rating of untreated check} - \text{disease rating of treatment or standard})}{\text{disease rating of untreated check}} \times 100$$

The percent disease control for a treatment was next compared with the percent control for the standard fungicide (captan at 0.24% w. of formulated chemical) as follows:

$$70 \frac{\text{percent control for treatment}}{\text{percent control for standard}} \times 100$$

75 Where the disease control for the test chemical and standard was equivalent, the index value was unity (100).

7
Values above 100 indicated superiority. It will be understood however that compounds showing index values substantially below 100 may also be considered of value.

In most cases comparisons were made at the 0.24% w. (2 lbs./100 gal.) concentration.

Readings for plant poisonings were obtained on tomato, bean, celery and cucumber. Both chronic toxicity (yellowing, distortion, etc.) and acute toxicity (tissue death) were recorded. The scale used was from 0-400; "0" represented no visible poisoning and 400 was the most severe manifestation.

The following table summarizes the results of these tests.

5 A further form in which the fungicidal compounds of the present invention may be applied consists of solutions of the active ingredient in suitable inert liquid or semi-solid diluents, in which the active ingredients are present in molecularly dispersed form. The form in which the agents to be employed are applied to the objects treated depends on the nature of the object and the purpose of the application.

10 Suitable inert solvents for the manufacture of liquid preparations should be inflammable, as odorless as possible and without any toxic effect on humans and animals when properly used. Neither should they have a corrosive effect on the components of the preparations or

The active compounds of the present invention may be used alone or in combination with other fungicidal, viricidal, insecticidal, or acaricidal materials, the action on which may be either internal or external, with plant nutritives, plant hormones and the like. Wetting agents, and if necessary or desirable, stickers such as the heavy hydrocarbons oils with a minimum viscosity of 10° Engler at 50° C. can be present. Any conventional wetting agent which will not react with the toxicant for example alkyl sulfate salts, alkyl aryl sulfonate salts, sulfosuccinate salts, ethers of polyethylene glycols and alkylated phenols, and the like can be employed. If the toxic agents are employed in the form of emulsions or suspensions, for example, in water, solvents such as oils, emulsifiers, emulsion stabilizers and the like may be added. Materials which suppress phytotoxic action 45 may also be added if desired. For example, glucose is known to protect tomato plants against damage by certain substances having a phytotoxic effect when employed in concentrated form.

55 The imides and maleimides of the present invention may be applied by means of spraying. Spraying of the plants to be treated may be performed with aqueous emulsions solutions or suspensions of the active agents. The spray liquid is generally applied at a rate of from about 75 to 150 gallons per acre. If spraying is effected with smaller quantities of liquid as in low volume spraying, high concentrations of the active agents should be employed. If desired, a minor amount of the order of about 0.01 to about 0.05% by weight, of a wetting agent may be added to aid in forming a suspension of the salt in the aqueous medium. Any of the conventional wetting agents can be employed. Particularly suitable wetting agents are the sodium salts of a mixture of secondary heptadecyl sulfates, sold commercially under the name of "Teepol" and polyethylene glycol ethers of alkyl phenols sold under the trade name of "Triton X-100" and "Triton X-155." Preferable concentrate compositions comprising an active compound of the present invention and a suitable wetting agent are prepared, and the concentrate is then dispersed in water prior to use.

40 the material of the storage vessel. Examples of suitable solvents are high boiling oils, e.g. oils of vegetable origin such as castor oil, etc., and lower-boiling solvents with a flash point of at least 30° C., such as carbon tetrachloride, ethylene dichloride, hydrated naphthalene, alkylated naphthalene, sorbent naphtha, etc. Mixtures of solvents may also be used.

45 The active compounds of the present invention may also be applied in the form of dusts utilizing as the inert vehicle such materials as tricalcium phosphate, precipitated chalk, bentonite, kieselguhr, etc.

These compounds may also be employed in the form of aerosols. For this purpose, the active ingredient is dissolved or dispersed in a solvent boiling below room temperature at atmospheric pressure.

50 We claim as our invention:

1. A polyhalo compound of the formula

65 wherein X is a member of the group consisting of hydrogen and halogen, and at least one X is halogen, X' is a member of the group consisting of hydrogen, halogen and lower alkoxy, R is selected from the group consisting of alkylene, phenylalkylene, tolylalkylene, naphthalenylalkylene and anthracenylalkylene in which alkylene is in each case alkylene of 1 to 10 carbon atoms, and tolylene, phenylene, naphthylene and anthrylene, y is a whole number from 0 to 1, and W is a member selected from the group consisting of alkylene of 2 to 5 carbon atoms, alkylene of 2 to 5 carbon atoms, halo-substituted alkylene of 2 to 5 carbon atoms, 1,2-phenylene, and n is a whole number from 0 to 1.

70

2. A compound of the formula

wherein W is straight-chain, halo-substituted alkylene of 2 to 5 carbon atoms.

3. A compound of the formula

wherein R is straight-chain alkylene of 1 to 10 carbon atoms.

4. A compound of the formula

wherein X and X' are each halogen.

5. A compound of the formula

5

wherein X and X' are each halogen.

10 6. N-(1,4,5,6,7,7-hexachlorobicyclo(2.2.1)hept-5-en-2-yl-methyl)maleimide.

7. 2-chloro-n-(1,4,5,6,7,7-hexachlorobicyclo(2.2.1)hept-5-en-2-ylmethyl)maleimide.

15 8. N-(5,6,7,8,9,9-hexachloro-1,2,3,4,4a,5,8,8a-octahydro-1,4,5,7-dimethanonaphthalen-2-ylmethyl)maleimide.

9. 2,3-dichloro-N-(1,4,5,6,7,7-hexachlorobicyclo(2.2.1)hept-5-en-2-ylmethyl)succinimide.

20 10. N-(1,4,5,6,7,7-hexachlorobicyclo(2.2.1)hept-5-en-2-yl)-maleimide.

11. The method of combatting fungi on living plants comprising applying a fungicidal toxic amount of N-(1,4,5,6,7,7-hexachlorobicyclo(2.2.1)hept-5-en-2-ylmethyl)maleimide to said plants.
